[57] **CLAIM**

The ornamental design for a tire tread, as shown and described.

DESCRIPTION

FIG. 1 is a perspective view of a tire tread showing our new design, it being understood that the pattern is repeated throughout the circumference of the tread, the opposite side being substantially the same as that shown; FIG. 2 is a front elevation view thereof;

FIG. 3 is an enlarged fragmentary front elevational view thereof; and

FIG. 4 is an enlarged fragmentary side elevational view thereof.

The broken lines in the drawings are for illustrative purposes only and form no part of the claimed design.
